Fig. 6.

UNITED STATES PATENT OFFICE.

ARCHIE H. BECHTOL AND WALTER A. TRATSCH, OF MEMPHIS, TENNESSEE.

AMUSEMENT DEVICE.

Application filed December 19, 1922. Serial No. 807,915.

To all whom it may concern:

Be it known that we, ARCHIE H. BECHTOL and WALTER A. TRATSCH, both citizens of the United States, residing at Memphis, in the county of Shelby and State of Tennessee, have invented certain new and useful Improvements in Amusement Devices; and we do hereby declare the following to be a full, clear, and exact description of the invention, such as will enable others skilled in the art to which it appertains to make and use the same.

This invention relates to an amusement device comprising a coin operated pistol and has for its object to provide an apparatus of this character which will be simple in construction, comparatively inexpensive to manufacture, and more efficient in use than those which have been heretofore proposed.

With these and other objects in view, the invention consists in the novel details of construction, and combinations of parts more fully hereinafter disclosed and particularly pointed out in the claims.

Referring to the accompanying drawings forming a part of this specification, in which like numerals designate like parts in all the views:

Figure 1 is a diagrammatic plan view of an apparatus made in accordance with this invention;

Figure 2 is a side elevational view, partly in section, of the apparatus shown in Figure 1;

Figure 3 is a side elevational view of the pistol portion of the device removed from its casing and showing a portion of said casing in dotted lines;

Figure 4 is a view of the parts shown in Figure 3 as seen from the opposite side;

Figure 5 is a plan view of the parts shown in Figure 4;

Figure 6 is a fragmentary side elevational view of a portion of the parts shown in Figure 3, when in their firing position;

Figure 7 is a view of the parts shown in Figure 6 as seen from the opposite side of the pistol;

Figure 8 is a sectional view of the pistol showing the trigger and hammer in positions ready to fire;

Figure 9 is a fragmentary perspective view showing the relation of parts in a position of rest; and

Figure 10 is a sectional view taken on the

line 10—10 of Figure 3, looking in the direction of the arrows.

1 indicates a coin chute with which the pistol is provided, 2 a coin that has passed down said chute and which must occupy the position shown in Figure 3 before the pistol can be fired. The controlling lever 3 is pivoted as at 4 and is provided with the toe or lug 5 which normally rests in the notch 6 with which the cam or lever 7 is provided, as will be clear from Figures 3 and 6. The shaft 8 has loosely mounted thereon the notched disk 9 and rigidly mounted thereon the cam or lever 7. The trigger 10 is pivoted as at 11, Figure 8, and pivoted to said trigger as at 12 is the member 13 which acts against the member 14 rigidly attached to the shaft 8, and therefore turns with said shaft. The cam 7 is cut away as at 15 to receive the rounded edge of the coin 2, which latter rests between said cam and the edge 16 of the lever 17 pivoted as at 4 and provided with the projection 18 adapted to take against the lever 3 as best shown in Figure 3. It results from the construction so far described that when the trigger 10 is pulled it will swing on its pivot 11, causing the arm 13 to push the arm 14 toward the left as seen in Figures 8 and 9, and thus turn the shaft 8 in a counter-clockwise direction, as seen in said figures. The rotation of the shaft 8 just described turns the cam 7 in the same direction, and thus pushes the coin 2 toward the left as seen in Figure 3. This movement of said coin moves the lever 17 and pin or projection 18 as well as the lever 3 toward the left as seen in said Figure 3, with the result that the toe 5 of said lever 3 is withdrawn from the notch 6 of the cam 7 against the tension of the spring 20.

As said cam 7 moves forward in the manner just described, it carries with it the spring pawl 21 secured as at 22 to said cam, and which turns the disk 9 one notch around the shaft 8. This said disk 9 has one notch 23 which is deeper than the others, and which when registering with the notch 6 in the cam 7 permits the toe 5 to lock said disk 9 and cam 7 together, but when not so in register permits the pawl 21 to rotate said disk 9 freely until said deep notch 23 is again brought into register with said cam notch 6. The toe 5 is sufficiently wide to span both the notches 6 and 23. It thus re-

60

sults that after the pawl 21 has thus turned the disk 9, one notch in moving the coin 2 as above disclosed, said deep notch 23 will no longer be in register with the notch 6 5 and said toe 5 will upon its return to the position shown in Figure 3, no longer lock the cam 7, but will rest in a shallow notch 24 of the said disk 9. In other words, it will be apparent that after the coin 2 has 10 once been placed in the gun and the trigger has, through the agency of said coin, released the cam 7 from the toe 5 then the trigger may be continuously operated until the pawl 21 has rotated the disk 9 through 15 a complete revolution and brought the deep notch 23 back into register with said notch 6. That is, after one coin has been expended five shots can be fired with the five notches in disk 9.

20 The arm 13 is controlled by the heavy spring 30 carried by the trigger, and the arm 14 is controlled by the spring 31 as shown. Pivoted as at 32 is a gravity controlled sear or tripping member 33 provided 25 with an inclined face 33^a and a shoulder 34 against which takes the beveled lower end 35 of the hammer member 38 also pivoted at 32 and controlled by the spring 36. It thus results that as the members 13 and 14 30 move forward as disclosed, they swing the tripping member 33 on its pivot 32 and thus through its shoulder 34 pressing on the bevelled edge 35 of the hammer member 38 swings the latter on its pivot against the 35 compression of the spring 36. This action will continue until the toe 40 of the member 14 passes the sear or tripping member 33 and thus releases the hammer 38 which fires the shot. Upon releasing the pressure on 40 the trigger 10, the spring 31 forces back the member 14 causing the toe 40 thereof to contact the inclined surface 33^a of the tripping member 33, lift the latter and thus pass by, whereupon the said tripping member 45 will fall to its operative position. In its return movement the member 14 pushes back member 13 and so restores the trigger 10 to its initial position.

It is preferred to mount the gun 44 for 50 swinging around a vertical pivot 45, and a horizontal pivot 46, see Figure 2, in a manner the same as that disclosed in the copending application Serial No. 514,746, filed by Tratsch and Bechtol, November 12, 1921, 55 entitled "Amusement device." It is also preferred to partially enclose the gun between an upper transparent member 47 and a lower curved inclined metal tray 48 provided with a groove 49 to return the balls. 60 Any suitable target 50 may be provided, and any suitable screen 51 having holes 52 through which the balls may pass, may be positioned in front of said target. Those balls that miss the holes 52 will fall in front 65 of the screen 51 onto the tray and be re-

turned to the groove 49, while those balls that pass through said holes and strike the target 50 pass under the screen 51 through the space 53 and return to said groove 49. It thus results that the gun being mounted 70 on a universal pivot may be elevated or depressed and moved sidewise in exercising skill to hit the target and in all cases the balls will, through gravity, find their way back to the groove 49 in the tray 48. 75

The shaft 8 is also provided with a rocking member 54, Figure 4, having a toothed sector 55 adapted to engage the pawl 56 pivoted as at 58 and controlled by the spring 59. Said rocking member 54 is also provided with a curved shoulder 60 adapted to take against the toe 61 of the lever 62 pivoted at 58, and controlled by the spring 63. 64 represents a stop against which the lever 62 takes in its downward movement. 85 The extreme end 65 of the lever 62 takes between the forked ends 66 of a lever 67 pivoted at 68 to the frame, and at 69 to the pusher member 70, controlled by spring 78, all as will be clear from Figures 4, 7, and 10. 90 Said member 70 is provided with a toe 71 which acts like a reciprocating pawl to take under the pins 72 with which the cylinder 73 of the pistol is provided, and to thus rotate said cylinder each time the trigger is 95 pulled. A locking pawl 79, controlled as by spring 79^a is also pivoted at 68 and is adapted to extend into the depression or pocket formed by any two of the chambers or openings 80 of said cylinder, all as will 100 be clear from Figures 3 and 10. Thus it will be seen that as the pusher member 70 rotates the cylinder, the locking pawl 79 rides outwardly from one of the aforementioned pockets and then snaps into the next 105 adjacent pocket, thereby locking the cylinder 73 against reverse rotation upon the downward return movement of the said pusher member.

Said cylinder is pivoted as at 74 to the 110 frame of the gun, and also hung from said pivot is the frame member 75 carrying the funnel shaped member 76 beneath the barrel 77 of the gun. Said funnel shaped member 76 is normally in register with the 115 groove 49 of the tray 48 as indicated in dotted lines in Figure 3, but is spaced therefrom as indicated at 76^a by a distance less than the diameter of the ball so that the gun may be swung on its horizontal pivot indicated at 46, Figure 3, sufficiently to enable the operator to try his skill in shooting. 120

It will be clear from the foregoing that upon the pulling of the trigger, the piece will be unlocked when a coin 2 is in position, 125 as shown in Figure 6, and the hammer 38 will be cocked and fired in the manner above disclosed. But these actions involve the turning of the shaft 8 as described, and the turning of said shaft, as will be clear from 130

Figures 4, 7 and 10, will cause the toothed sector 55 to engage the pawl 56 and thus compel a complete stroke of the trigger 10 before the parts can be released. That is to say, these parts constitute a well known "complete stroke device" used in registers or counting machines. It operates as follows: The toe of the pawl 56 must keep in engagement with the rack 55 so long as the latter moves in a clockwise direction as seen in Figures 4 and 7, or until the rack passes entirely from under the pawl, thus causing a "complete stroke" of the trigger 10. When the rack does pass from under the pawl, however, the spring 59 turns the rack engaging end of pawl 56 on its pivot 58 in a clockwise direction, as seen in said last named figures, and thereby enables the rack 55 and trigger to return to their normal positions. The parts are so timed that when the rack has thus completed its first mentioned or forward movement the hammer is ready to fire, and a slight additional movement of the trigger fires the ball and the spring 59 thereupon moves the pawl 56 in the manner stated and permits the shaft 8 to return to its normal position. Further, the movement of the said sector toward the right, as seen in Figure 4, will cause its shoulder 60 to contact with the toe of the lever 62, thus swinging the lever 67 on its pivot 68 and raising the pawl member 70 sufficiently to turn one of the openings 80 in the cylinder 73 a predetermined angular distance to provide a register with the bore 81 of the gun. In the meantime, balls 82 that may have been fired at the screen 51 or target 50 will have returned to the groove 49 in the plate 48 in the manner above disclosed, and delivered from said groove into the funnel shaped member 76, see Figure 3, whence they will move into the lowest opening 80 of the cylinder 73, whence they will be moved successively by the pawl 71 up to the highest opening 85 of said cylinder and thus by gravity roll into the bore 81 of the gun. In this manner, as each shot is fired a new ball is delivered into the lowest opening 80 of the cylinder and another ball is passed from the highest opening 85 into the bore so that the gun is automatically loaded after each shot.

Up to this point, however, the description of the gun has been limited to its operation upon the application of a coin to unlock the mechanism. Should the trigger be pulled with no coin inserted, damage to said mechanism is prevented by operation of the member 13, as best illustrated in Figures 3, 8 and 9. That is to say, the mechanism is normally intended for use only after the insertion of a coin which, as stated previously, causes the lug 5 to disengage the notch 6 of the cam 7 and thus allowing the shaft 8 to be rotated. But if, on the other hand, should the trigger be pulled when no coin has been

introduced to disengage the said lug 5 from the cam 7, shaft 8 will remain locked against rotation and consequently member 14, which is rigidly attached to the said shaft will not turn. Therefore, member 13 slips or rides over the curved rear surface 41 of the toe 40 of member 14 against the compression of the heavy spring 30, see Figure 9.

It will thus be seen that no damage can result, nor no shot be fired, when member 13 so rides over the member 14, inasmuch as the toe 40 of said member 14 extends above the sear or tripping member 33 of the hammer 38. In other words, the members 12, 13, 14, 30 and their coacting parts constitute a safety means or device which prevents damage to the mechanism when the trigger is pulled while the parts are locked. In this connection, it might be further added that the spring 30 must of course be much stronger than springs 31 and 36.

It is obvious that those skilled in the art may vary the details of construction as well as the arrangement of parts, without departing from the spirit of the invention, and therefore it is not desired to be limited to the above disclosure except as may be required by the claims.

What is claimed is:

1. In an amusement device, the combination of a propelling device; a trigger controlling said propelling device; means for pivoting said device for movement in a horizontal plane; means for pivoting said device for movement in a vertical plane; means to normally lock the mechanism; a safety means comprising a spring controlled pivoted member and preventing injury to said mechanism when the trigger is pulled while the parts are locked; a target toward which balls may be fired from said device; and means for automatically returning the fired balls to said device.

2. In an amusement device, the combination of a propelling device comprising a barrel and a spring controlled hammer member; a trigger and sear member controlling said propelling device; means for pivoting said device for movement in a horizontal plane; means for pivoting said device for movement in a vertical plane; means to normally lock the mechanism; a safety means comprising a spring controlled pivoted member and preventing injury to said mechanism when the trigger is pulled while the parts are locked; a target toward which balls may be fired from said device; and means for automatically returning the fired balls to said device.

3. In an amusement device, the combination of a propelling device comprising a barrel and a spring controlled hammer; a trigger and sear member controlling said propelling device; means for pivoting said device for movement in a horizontal plane;

means for pivoting said device for movement in a vertical plane; means to normally lock the mechanism; a safety means comprising a spring controlled pivoted member 5 and preventing injury to said mechanism when the trigger is pulled while the parts are locked; a target toward which balls may be fired from said device; and means comprising a grooved tray for automatically 10 returning the fired balls to said device.

4. In an amusement device, the combination of an operating shaft; provided with an arm like member rigid therewith; means for normally locking said shaft; a propelling device adapted to be actuated by said 15 arm like member; a trigger provided with a spring controlled pivoted member adapted to actuate said arm like member when said shaft is not locked and to serve as a safety 20 device when said shaft is locked to prevent injury to the mechanism when the trigger is pulled while said shaft is locked; means for pivoting said device for movement in a horizontal plane; means for pivoting said 25 device for movement in a vertical plane; a target toward which balls may be fired from said device; and means for automatically returning the fired balls to said device.

5. In an amusement device, the combination of a gun; means for pivoting said gun for movement in two planes at right angles to each other; a target; means carried by said gun for firing balls at said target; an operating shaft; means to normally lock 35 said shaft; means carried by said shaft for firing said gun; a trigger provided with means for actuating said shaft when said shaft is not locked, said last named means constituting a safety device to prevent injury to the mechanism when said shaft is 40 locked; a pivoted sear coacting with said trigger; and means for automatically returning to said gun the fired balls.

6. In an amusement device, the combination of a gun provided with a revolving cylinder; means for pivoting said gun for movement in two planes at right angles to each other; a target; means carried by said gun for firing balls at said target; an operating shaft; means to normally lock said 50 shaft; means carried by said shaft for firing said gun; means carried by said shaft for revolving said cylinder; a trigger provided with means to actuate said shaft; said means 55 also constituting a safety device to prevent injury to the mechanism when said trigger is pulled while said shaft is locked; a pivoted sear coacting with said trigger; and means for automatically returning to the 60 cylinder of said gun the fired balls.

7. In an amusement device, the combination of a gun; means for pivoting said gun for movement in two planes at right angles to each other; a target; means carried by 65 said gun for firing balls at said target; an

operating shaft; means carried by said shaft for firing said gun; means to normally lock said shaft; a trigger provided with means for actuating said shaft, said means also constituting a safety device to prevent injury to the mechanism when said trigger is pulled while said shaft is locked; means carried by said shaft for compelling a complete 70 operating stroke of said trigger when the latter is moved; and means for automatically 75 returning to said gun the fired balls.

8. In an amusement device, the combination of a gun; means for pivoting said gun; means for normally locking the mechanism; a pivoted trigger carried by said gun; a pivoted hammer carried by said gun; a pivoted spring controlled means carried by said trigger; a pivoted gravity controlled means carried by said hammer; and connections by which said trigger carried means 85 causes the actuation of said hammer carried means when the machine is unlocked and, whereby when said connections are locked the trigger may be pulled without injury 90 to the mechanism.

9. In an amusement device, the combination of a gun provided with a revolving cylinder; means for pivoting said gun; a pivoted trigger carried by said gun; a pivoted hammer carried by said gun adapted 95 to fire balls therefrom; a pivoted spring controlled means carried by said trigger; a pivoted gravity controlled means carried by said hammer; an operating shaft; connections by which said trigger carried means 100 causes the actuation of said hammer carried means; means for locking said connections; means associated with said shaft for revolving said cylinder; and means for returning the fired balls to said cylinder, whereby 105 when said connections are locked the trigger may be pulled without injury to the mechanism and whereby when said connections are not locked a pull on the trigger will 110 fire the gun and turn said cylinder.

10. In a gun for use in an amusement device, the combination of a barrel; a spring controlled pivoted hammer for propelling balls out of said barrel; a gravity controlled sear carried by said hammer; a trigger coacting with said sear; an operating shaft actuated by said trigger; a rotating cylinder; and connections between said shaft and cylinder for rotating the latter.

11. In a gun for use in an amusement device, the combination of a barrel; a spring controlled pivoted hammer for propelling balls out of said barrel; a pivoted sear carried by said hammer; a trigger coacting with said sear; an operating shaft actuated by said trigger; means for normally locking said shaft against operation; a rotating cylinder; and connections between said shaft and cylinder for rotating the latter when said shaft is free to turn.

12. In a pistol for use in an amusement device, the combination of a barrel; a spring controlled hammer for firing balls out of said barrel; a gravity controlled sear carried by said hammer; a trigger; an operating shaft; means carried by said trigger for turning said shaft; means carried by said shaft for placing said hammer under the force of its spring; a cylinder; means carried by said shaft for rotating said cylinder; and means for automatically locking said shaft against rotation after a predetermined number of balls have been fired. 40
13. In a pistol for use in an amusement device, the combination of a barrel; a spring controlled hammer for firing balls out of said barrel; a trigger; an operating shaft; means carried by said trigger for turning said shaft; means for compelling a complete stroke of said trigger after its operating movement has begun; means carried by said shaft for placing said hammer under the force of its spring; a cylinder; means carried by said shaft for rotating said cylinder; and means for automatically locking said shaft against rotation after a predetermined number of balls have been fired. 50
14. In a pistol for use in an amusement device, the combination of a firing mechanism comprising a gravity controlled sear; a barrel; a cylinder adapted to receive balls and to deliver them to said barrel for firing; a funnel shaped member carried by said pistol adapted to receive the fired balls and to deliver them into said cylinder; a trigger coacting with said sear; and connections by which said cylinder will be rotated upon the operation of said trigger. 55
15. In a pistol for use in an amusement device, the combination of a barrel; a cylinder adapted to receive balls and to deliver them to said barrel for firing; a funnel shaped member carried by said pistol adapted to receive the fired balls and to deliver them into said cylinder; a trigger coacting with said sear; and connections comprising means for compelling a complete stroke when the trigger is moved by which said cylinder will be rotated upon the operation of said trigger. 60
16. In a pistol for use in an amusement device, the combination of a firing mechanism comprising a gravity controlled sear; a barrel; a cylinder adapted to receive balls and to deliver them to said barrel for firing; a funnel shaped member carried by said pistol adapted to receive the fired balls and to deliver them into said cylinder; means for pivoting said pistol for movement in a vertical plane at the mouth of said funnel; a trigger coacting with said sear; and connections by which said cylinder will be rotated upon the operation of said trigger. 65
17. In an amusement device, the combination of a pistol adapted to fire balls at a target; a tray over which said balls may be fired provided with a groove for returning the fired balls to said pistol; a funnel carried by the pistol for receiving said balls from said groove; and means for pivoting said pistol for movement around an axis passing between the ends of said groove and funnel. 70
- In testimony whereof we affix our signatures. 75
